UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

ROTATING DEVICE FOR PERCUSSIVE TOOLS.

1,375,444.

Specification of Letters Patent. Patented Apr. 19, 1921.

Application filed March 22, 1920. Serial No. 367,825.

To all whom it may concern:

Be it known that I, LEWIS C. BAYLES, a citizen of the United States, residing at Easton, in the county of Northampton and 5 State of Pennsylvania, have invented a certain new and useful Improvement in Rotating Devices for Percussive Tools, of which the following is a specification.

This invention relates to fluid actuated 10 percussive tools, but more particularly to rotating devices and connections for imparting rotation to the drill steel.

The objects of the invention are to simplify and reduce the number of parts in the 15 train of operative connections required to transmit rotative motion from a motor or source of power to the drill steel, and avoid as far as possible counter shafts and gearing external to the piston chambers of the tool.

Another object of the invention is to utilize 20 an anvil block as one of the rotating elements for transmitting rotation to the drill steel.

To these ends and in order to carry out 25 further objects of the invention which will hereinafter appear, the invention consists of the combinations of elements shown in one of their preferred forms in the accompanying drawings in which—

Figure 1 is a side view partly broken away 30 and partly in longitudinal section of so much of a drill casing and front head as will serve to show the invention,

Fig. 2 is a transverse sectional view on 35 the line 2—2 of Fig. 1, and

Fig. 3 is a transverse sectional view on the line 3—3 of Fig. 1.

Referring to the drawings, A represents 40 the cylinder casing of a percussive tool, in this instance a rock drill, and B represents the striking end of the piston hammer adapted to reciprocate in the cylinder and preferably fluid actuated although the means for supplying and distributing the motive fluid 45 under pressure are not shown as forming no part of the present invention. The front head C of the tool is suitably secured to the cylinder casing A by the usual side bolts D and the drill steel F is held in the rotating 50 chuck G within the front head.

Between the front head and drill cylinder casing an anvil block seat H is preferably secured, and an anvil block J lies with-

in the chuck G and is guided in the seat H. The anvil block J has slidable and non-rotative engagement with the chuck G and in this instance and as a convenient construction the anvil block is provided with flutes or ribs K engaging internal grooves L in the chuck G. 55 60

A rotating shaft O passes through the piston B and slidably but non-rotatably engages the anvil block J, in this instance, the shaft O having flutes P at its inner end engaging internal ribs or flutes Q in the anvil 65 block J, so that rotation of the shaft O imparts rotation to the anvil block J, the chuck G and the drill steel F. The usual water tube R passes through the parts as shown for conducting cleaning fluid to the 70 drill steel.

The construction is simple and efficient, easy to construct and assemble and not liable to get out of order.

Any suitable rotation motor (not shown) 75 may be provided for driving the rotating shaft O, and in accordance with my construction, the motor may be located in any convenient position on the tool, as for instance at the back end, which is a desirable location 80 in the majority of instances, particularly in stope drills. Furthermore, the outside of the drill casing and front head is kept smooth and external protuberances and bearings for driving connections are avoided. 85

I claim:

1. In a percussive tool, the combination of a cylinder casing, a piston reciprocating therein, an anvil block adapted to receive the impact of the piston, a chuck for receiving the drill steel, the chuck and anvil block having sliding but non-rotating engagement, and a rotating shaft passing through the piston and slidably but non-rotatably engaging the anvil block for imparting rotation to the drill steel. 95

2. In a percussive tool, the combination of a cylinder casing, a piston reciprocating therein, an anvil block adapted to receive the impact of the piston, a chuck for receiving the drill steel, the anvil block slidably engaging the chuck but rotatable therewith, and a rotating shaft passing through the piston and having a fluted end engaging flutes on the anvil block, whereby rotation 100 is imparted to the drill steel. 105

3. In a percussive tool, the combination of a cylinder casing, a piston reciprocating therein, an anvil block adapted to receive the impact of the piston, a chuck for receiving the drill steel, the anvil block slidably engaging the chuck but rotatable therewith, an anvil block seat, and a rotat-

ing shaft passing through the piston and having a fluted end centrally engaging flutes on the anvil block, whereby rotation is imparted to the drill steel. 10

In testimony whereof, I have hereunto set my hand.

LEWIS C. BAYLES.
